(57) **CLAIM**

The ornamental design for a network connector, as shown and described.

DESCRIPTION

FIG. 1 is a front perspective view of a network connector showing the new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a rear perspective view thereof; and,

FIG. 9 is a top perspective view thereof shown relative to a network cable.

The broken line showing of the network cable, in FIG. 9, illustrates environmental structure that forms no part of the claimed design.

1 Claim, 7 Drawing Sheets
